UNITED STATES PATENT OFFICE.

WILLIAM H. KELLER AND ALBERT SCHINKEZ, OF GRAND HAVEN, MICHIGAN,
ASSIGNORS TO KELLER PNEUMATIC TOOL COMPANY, OF GRAND HAVEN,
MICHIGAN, A CORPORATION OF MICHIGAN.

PISTON-ROD TOGGLE FOR FLUID-PRESSURE MOTORS.

1,398,328.

Specification of Letters Patent. Patented Nov. 29, 1921.

Application filed April 29, 1920. Serial No. 377,507.

To all whom it may concern:

Be it known that we, WILLIAM H. KELLER, a citizen of the United States, residing at Grand Haven, in the county of Ottawa and State of Michigan, and ALBERT SCHINKEZ, a former subject of the Emperor of Austria, residing at Grand Haven, in the county of Ottawa and State of Michigan, have invented certain new and useful Improvements in Piston-Rod Toggles for Fluid-Pressure Motors, of which the following is a specification.

This invention relates generally to a novel construction in fluid pressure motors of the type used in portable drills, pneumatic tools and the like, and relates more particularly to the piston rod connections, known as toggles, which coact with the crank shaft.

The primary object of this invention is to provide a simplified toggle construction and thereby materially lower the cost of manufacture and greatly increase the facility with which the toggles may be assembled or replaced in a complete motor.

Another object is to provide a strong and durable construction which will increase the life of the toggle under severe conditions of service.

These objects we attain by a novel structure the parts of which may be stamped out of sheet metal, and which comprise simplified and strengthened means of mounting on the piston rod and crank shaft wherein a considerable amount of labor is saved in the manufacturing, assembly and subsequent repair of a motor, and the life of the structure in service is increased.

It is the common practice, in motors of this class, to arrange a plurality of cylinders about a common crank shaft, the cylinders being angularly disposed in pairs in which the pistons are operatively connected with one crank bearing. Hinged toggles are usually employed, one overlying the other, which are secured to their respective piston rods by means of a binding nut engaging the toggle ends. In the usual construction it is found that the toggle hinges frequently shear off, and that the binding nuts split under the strain of service. Also, the toggles now commonly used are made of forged

ings requiring many machining operations in their manufacture, and they are very difficult to assemble in the motor due to 55 their design and the necessarily restricted space in the crank case.

These objectionable features are avoided in the structure disclosed in this invention, as will be apparent, with other advantages, 60 in the following specification of one embodiment of the invention.

In the drawings, Figure 1 represents in sectional view a pair of pistons, showing the piston rods and toggle connections in elevation. The cylinders, valve mechanism and crank case are indicated in outline as embodied in the preferred structure described in our pending application, Serial No. 228,570, filed April 15, 1918. Fig. 2 represents a side elevation of a piston rod with toggle assembly as viewed on line 2-2 in Fig. 1. Fig. 3 represents in perspective the parts of a pair of toggles and piston rod connections.

In Fig. 1, numerals 1 and 2 indicate a pair of cylinders arranged with their axes at an angle and in a common plane. The pistons 3 and 4 operating therein carry piston rods 5 and 6 to which are secured the 80 toggles 7 and 8. Toggle 7 has its bearing directly upon the crank journal 9, while toggle 8 overlies and has its bearing upon toggle 7. A valve mechanism associated with the cylinders is indicated at 10. The 85 crank case, indicated at 11, has two lateral openings 12, which are closed by removable plates and designed to provide access for the assembly or repair of the toggle connections.

The toggles are of two piece construction. The inner toggle 7 comprises two members 13 and 14 (Fig. 3) each forming half of the bearing 15 and 16 and having lateral extensions 17 and 18. The extensions are perforated at 19 and 20 to receive a clamping bolt. The member 14 has a tongue 21 formed on its outer edge adapted to engage a recess 22 formed in the abutting edge of the member 13, designed to secure them in 100 relative position when assembled. Oiling holes are provided at 23 and 24. Journals are formed at 25 and 26 for the bearings of the overlying toggle 8.

In assembled position the extensions 17 and 18 abut on their inner faces and are adapted to be rigidly clamped to the piston rod by engagement within and abutting the base of the yoke formed by the recess 27 cut in the outer end of the piston rod. The yoke arms are bored transversely at 28, in register with the holes 19 and 20 in the toggle members. The assembly is secured 10 in position by the clamping bolt 29, having threaded engagement with the yoke. A lock washer 30 may be seated in a recess 31 formed on the yoke, and provided with straps 32 which may be bent up against the lateral faces of the bolt head. A slot 33 may be cut longitudinally at the base of the recess 27, to give uniform bearing of the yoke arms in clamping the toggle members.

The outer toggle 8 also comprises two members 34 and 35, having lateral extensions 36 and 37, perforated at 38 and 39. The two members 34 and 35 are secured to their respective piston rod by means similar to that just described for the members in 25 the inner toggle 7. The members 34 and 35 are formed with curved straps 40 and 41 whose internal surfaces are adapted to bear upon the journals 25 and 26 formed on the inner toggle members. In assembled position 30 the extensions 17 and 18 on the inner toggle members extend through the aperture formed between the straps 40 or 41, as may be selected, and operatively swing therein. The straps 40 are integrally connected at their outer ends by a cross bar 42 which extends the full width of the member and is raised above the outside contour of the straps. The straps 41 also are integrally connected at their outer ends by a cross bar 40, on which is carried a curved portion 45 forming an outwardly curved hook adapted to engage the bar 42 between the straps 40, thus positively securing the engagement of the members 34 and 35 in their assembled 45 position about the underlying toggle members.

It will be seen that we have produced a simplified toggle structure which will be apparent to one skilled in the art as being 50 capable of manufacture by simple stamping from sheet metal. It will be evident also that the method of connecting the toggle members to the piston rod greatly simplifies their assembling and repair in a motor, in 55 that the few necessary operations may be quickly and conveniently done through the openings provided in the crank case. This connection likewise provides great rigidity and durability. A further apparent advantage lies in the integral connection in each 60 member of the outer ends of the straps forming the outer toggle bearings, together with the integral interlocking bar extending the full width of the toggle member and the 65 wide hook engaging therewith, thereby pro-

viding a strong durable engagement at a point of considerable strain.

We would have it understood that the invention is not limited to the construction herein shown, as various modifications may 70 be made within the scope of the appended claims.

We claim as our invention:—

1. A fluid pressure motor having two cylinders in angular relation to each other, 75 pistons therein, a crank shaft and a crank case, in combination with two piston rods each having an end connected with one of said pistons, the opposite end carrying clamping means, a separable part toggle connection bearing upon said crank shaft and rigidly clamped to one of said piston rods, a separable part toggle connection having spaced curved portions bearing upon the first mentioned toggle connection and 85 rigidly clamped to the other of said piston rods, interengaging means for locking in operative position the outer ends of the separable parts of the second mentioned toggle connection, said means comprising integral 90 bars extending across the outer ends of said curved portions, one of said bars carrying an outwardly curved hook adapted to engage the other of said bars between its said curved portions and interlock therewith, and lateral 95 detachably covered openings through said crank case arranged to expose said toggle connections.

2. Means for connecting a crank with a pair of reciprocating elements comprising an 100 inner toggle and an outer toggle stamped from sheet metal, the inner toggle composed of two complementary members each having a semicylindrical bearing portion adapted to embrace the crank and a lateral projection adapted for attachment to a connecting rod, the outer toggle composed of two complementary members each having spaced 105 curved portions adapted to embrace the bearing portion of the inner toggle, and a 110 lateral projection adapted for attachment to a connecting rod, the outer ends of the curved portions in one member being integrally joined to form a cross bar of the full width of said member, the other of said 115 members having its complementary curved portions integrally joined to form an outwardly curved hook adapted to pass inwardly of said bar between its adjoining curved portions and interlock the members 120 in operative position.

3. In a fluid pressure motor, an outer toggle connection comprising two complementary members stamped from sheet metal, each of said members having two spaced 125 straps cylindrically curved and adapted to embrace in bearing engagement an inner toggle, the straps being integrally joined at their ends by cross elements, one pair of cross elements carrying lateral means of attachment 130

to a piston rod, the other pair of cross elements having means for interlocking the outer ends of the toggle members comprising an outwardly curved hook formed on 5 one cross element adapted to extend between the spaced straps adjoining the other cross element and engage the latter cross element

to prevent the separation of said complementary members when secured in operative position.

In testimony whereof we have hereunto set our hands.

WILLIAM H. KELLER.
ALBERT SCHINKEZ.
